UNITED STATES PATENT OFFICE.

HENRY J. CASE, OF OWASCO, ASSIGNOR TO THE JOHNSTON HARVESTER COMPANY, OF BATAVIA, NEW YORK.

SHEAF-CARRIER.

SPECIFICATION forming part of Letters Patent No. 553,053, dated January 14, 1896.

Application filed March 25, 1895. Serial No. 543,065. (No model.)

To all whom it may concern:

Be it known that I, HENRY J. CASE, a citizen of the United States, residing at Owasco, in the county of Cayuga and State of New York, have invented new and useful Improvements in Sheaf-Carriers, of which the following is a specification.

This invention relates to that class of sheaf-carriers which are used on grain harvesting and binding machines, and which consist of laterally-projecting receiving-fingers, which are connected by upright pivots to a rocking bar arranged longitudinally on the stubbleward side of the machine, and which are held in a substantially horizontal position for receiving the sheaves or bundles and are dropped with their outer ends to the ground by the rocking movement of the supporting-bar for discharging the sheaves, and are then swung backwardly and toward the side of the machine on their individual pivots by the forward movement of the machine, and are so withdrawn from underneath the sheaves.

My invention has for its object to improve the construction and operation of this class of sheaf-carriers in various respects.

In the accompanying drawings, consisting of two sheets, Figure 1 is a fragmentary rear elevation of a grain-harvester provided with my improved sheaf-carrier. Fig. 2 is a top plan view of the same. Fig. 3 is a top plan view of the sheaf-carrier on an enlarged scale. Fig. 4 is a transverse section, on an enlarged scale, in line 4-4, Fig. 3, looking rearward and showing the position of the parts when the carrier receives the bundles from the binder mechanism. Fig. 5 is a similar view showing the position of the parts when the carrier is dropped for discharging the bundles on the ground. Fig. 6 is a sectional front view of one of the fingers and connecting parts corresponding to Fig. 4. Fig. 7 is a similar view corresponding to Fig. 5. Fig. 8 is a fragmentary vertical section of the connection between the connecting-bar and one of the fingers.

Like letters of reference refer to like parts in the several figures.

A represents the main frame of a harvester; B the driving-wheel, and C the inclined binder-deck, upon which the grain is tied into bundles by any suitable and well-known mechanism.

The sheaf-carrier, whereby the bundles are collected before dropping the same upon the ground, is arranged below the delivery portion of the binder-deck and constructed as follows: D represents a longitudinal rock-shaft arranged horizontally underneath the delivery portion of the binder-deck and journaled with its ends in bearings d d' on the main frame. E represents the fingers of the carrier, which are attached to this shaft and project laterally from the side of the machine. Each finger is attached to the rock-shaft by 65 a sleeve F arranged on the rock-shaft and provided with a depending arbor f, which is embraced by an eye e formed on the inner end of the finger. The eye is confined on the arbor by a washer f' at the lower end of the arbor, and the washer and sleeve are secured to each other and to the rock-shaft by a single bolt g passing through these parts. The eye fits on the arbor sufficiently loose to permit the finger to swing not only backwardly and forwardly, but also vertically, as indicated by dotted lines in Fig. 4.

H represents a supporting-loop formed on the outer side of the sleeve and supporting the finger at a short distance from the eye. This loop is provided at its front end with a depressed seat h, which receives the finger in its normal operative position at right angles to the rock-shaft and holds it in that position. The loop is also provided with a cam or incline i which rises rearwardly from the seat h and over which the finger rides upwardly when the finger is swung rearwardly and inwardly. In their normal operative position the fingers project horizontally and at right angles to the rock-shaft and rest in the seats h of the loops, as represented in full lines in Figs. 1, 2, 3, 4 and 6. When the desired number of bundles have been delivered upon the fingers the rock-shaft is turned in the direction of the arrow, Fig. 1, whereby the fingers are caused to drop with their outer ends upon the ground, as represented in dotted lines in Fig. 1. The rock-shaft is turned through a somewhat greater arc than is necessary to drop the ends of the fingers upon the ground, so that when the fingers have reached the ground the loops will continue to move downwardly for a sufficient distance to disengage the fingers from the seats h of the loops. In this position of the parts the fingers stand

above the lower portions of the loops, as indicated in Fig. 5 and by dotted lines in Fig. 6. During the following forward movement of the harvester the fingers trail on the ground and move inwardly or toward the rock-shaft to the position indicated by dotted lines in Fig. 3 and by full lines in Figs. 5 and 7, thereby disengaging themselves from the bundles and depositing the latter upon the ground.

10 During this inward movement of the fingers the latter move at first horizontally above the lower portions of the loops and then come in contact with the rear portions of the loops and ride up on the latter, or the fingers may not ride up on the rear portions of the loops at all, as this depends somewhat upon the position of each finger with reference to its loop, which position in turn depends upon the support it finds upon the ground. When the 20 parts are in this position and the rock-shaft is turned in the proper direction to raise the fingers from the ground, the first portion of the return movement of the rock-shaft causes the cams of the loops to swing the fingers 25 forwardly until they engage in the seats of the loops and stand again at right angles to the rock-shaft. The further elevating movement of the rock-shaft causes the fingers to swing upwardly with the rock-shaft until they 30 reach their normal horizontal position.

Each supporting-loop is provided in front of the finger-seat with an upright face or shoulder *i* which limits the forward movement of the fingers. If the fingers strike an 35 obstruction when in their operative position they are turned on their pivots and folded inwardly and are at the same time raised by riding upon the cams. When the fingers have cleared the obstruction they ride down the 40 cams by gravity and so return to their normal position automatically.

J represents a longitudinal connecting-bar whereby the fingers are caused to move together, each finger being connected with the 45 bar by an eye *j*, through which the finger passes and which is pivoted to the bar by a pin *j'*. The connecting-bar is held at the proper distance from the rock-shaft by links *j''*, which connect the bar with the rock-shaft.

50 The return of the fingers to their normal position is preferably facilitated by means of a spring *k*, which is secured with its ends to the connecting-bar and one of the washers of the finger-arbors, which washer is provided for 55 that purpose with an opening into which the end of the spring is hooked. As the bundles slide off from the folded fingers some of the grain is apt to become caught in the sleeves and connecting parts on the rear portion of 60 the rock-shaft, and in order to avoid this the rear portion of the connecting-bar is provided with a shield or guard *L* which prevents the grain from coming into contact with the sleeves on the adjacent portion of the rock-shaft.

65 *M* represents a depending rock-arm which is secured to the rear end of the rock-shaft.

N N' represent a pair of toggle-bars or retaining-links whereby the fingers are held in their operative position. These bars are pivoted to each other by a pin *n*, while their opposite ends are pivoted, respectively, to the free end of the rock-arm *M* and to a standard *n'* arranged on the main frame. The inner end of the outer bar, *N*, projects beyond the 70 pivot connecting the bars and is provided near the driver's seat with a foot-piece *n''*. Upon depressing the bars the latter are straightened and the rock-arm is turned so as to bring the fingers into their operative position.

o represents a stop which is formed on the inner toggle-bar, *N'*, and arrests the downward movement of the bars when the latter have been depressed to their locking position 85 in which they hold the fingers in their normal horizontal position. The toggle-bars are unlocked for dumping the bundles by lifting the foot-piece of the outer bar by the foot.

P represents a stop which is formed on the outer end of the outer toggle-bar, *N*, and which projects upwardly on the outer side of the rock-shaft. As the toggle-bars are raised the outer bar moves inwardly until this stop strikes against the rock-shaft and so prevents 95 the further turning of the rock-shaft in the direction in which the fingers are lowered. This stop is so arranged that it prevents the downward movement of the fingers below a certain position and so prevents the fingers 100 from dropping into abnormal depressions in the ground and becoming injured thereby.

I claim as my invention—

1. In a sheaf carrier, the combination with a rock shaft, of a downwardly projecting arbor, a cam or loop projecting outwardly from said shaft, and a carrying finger passing over said cam or loop and provided on its inner end with an eye by which the finger is loosely attached to said arbor, substantially as set 105 forth.

2. In a sheaf carrier, the combination with a rock shaft and the carrying fingers pivoted thereto, of a bar connecting said fingers and a guard or shield secured to the rear fingers 115 outside of their pivots, substantially as set forth.

3. In a sheaf carrier, the combination with the main frame, a rock shaft journaled on the main frame and provided with a rock arm and carrying fingers connected with said shaft, of locking toggle bars connecting said rock arm with the main frame, and a stop formed on the outer toggle bar and adapted to strike against the rock shaft and limit the downward movement of the fingers, substantially 120 as set forth.

Witness my hand this 21st day of March, 1895.

HENRY J. CASE.
